HARRY ARTHUR FOOTHORAP, OF HARRISBURG, PENNSYLVANIA, ASSIGNOR TO ELLIOTT-FISHER COMPANY, OF HARRISBURG, PENNSYLVANIA, A CORPORATION OF DELAWARE.

LINE-SPACING MECHANISM.

1,275,413.

Specification of Letters Patent. Patented Aug. 13, 1918.

Application filed December 14, 1914. Serial No. 877,214.

To all whom it may concern:

Be it known that I, HARRY ARTHUR Foothorap, a citizen of the United States of America, residing at Harrisburg, in the county of Dauphin and State of Pennsylvania, have invented certain new and useful Improvements in Line-Spacing Mechanism, of which the following is a specification.

This invention relates to line spacing mechanism for typewriters and more particularly to typewriters of that class which includes a stationary flat platen and downwardly acting printing mechanism mounted to travel over the platen for line spacing and letter spacing of the printed record.

An object of the invention is the equipment of a typewriter with a simple and efficient line spacing mechanism capable of both fixed and universal line spacing and having practically all of its component elements assembled directly on the line space shaft.

Another object is to so organize the line space mechanism that the principal elements of the latter may be assembled in rear of the line space frame and supported by the combination corner brackets of said frame, the line space key or handle being located at the front of the frame and having operating connections extending therefrom to the elements assembled in rear of the frame.

Other objects will appear as the succeeding description is developed.

In the accompanying drawings:—

Figure 1 is a plan view of a line space frame mounted on a subjacent track frame and equipped with line spacing mechanism constructed in accordance with my invention.

Fig. 2 is a side elevation of a line spacing mechanism with the operating handle or key and part of the line space rock shaft broken away.

Fig. 3 is a rear elevation of the subject matter of Fig. 2.

Fig. 4 is a sectional view through the right hand combination bracket of the line space frame with the adjacent portion of the line space shaft in full lines and the associated elements of the line spacing mechanism in section.

Fig. 5 is a detail perspective view of a portion of the right hand combination

bracket with the rear line space bracket attached thereto.

55

Fig. 6 is a sectional view showing the connection between the transfer arm of the line space driver and the transfer plunger.

Fig. 7 is a detail perspective view of most of the elements of the line space mechanism, 60 said elements being grouped to indicate their relation but separated to facilitate the detailed illustration.

Fig. 8 is a bottom plan view of the right hand end of the line space frame showing 65 the mounting of the line drive shaft and the line space key.

1 indicates a track frame upon which is movable in the proper direction for line spacing, a line space frame 2 comprising 70 front and rear members 3 and 4 and side members 5 and 6. At the rear corners of the frame 2 are combination brackets 7 and 8 which constitute elements of the line space frame and afford bearings or supports for 75 several of the adjunctive mechanisms of the typewriter.

The mechanism with which we are directly concerned at this time is the line spacing means which is that group of elements controlled by the operator to effect a forward or line space step by step advance of the frame 2 on the track frame 1. The primary element of this mechanism is what is known as the line space shaft 9 which, in the present construction, is afforded bearings in the brackets 7 and 8 and is equipped with rear frame rollers 10 which travel on the track frame, and line space pinions 11, the teeth of which engage toothed racks 12 on the 90 track frame. The rollers 10 and pinions 11 are fixed in any suitable manner to rotate with the shaft 9 so that when said shaft 9 is rotated in the manner to be hereinafter described, the line space frame 2 of the machine will be compelled to move forward to properly line space the record made by the printing mechanism which, in this type of machines, is downwardly acting and is mounted on a carriage, indicated at C in Fig. 100 2, said carriage being movable with the line space frame in the direction of line spacing and also movable upon said frame to letter space the writing in a manner well understood in the art.

100

The shaft 9 is rotated by the manipula-

105

tion of a line space key or handle 13 located adjacent to the right hand front corner of the frame. This handle or key 13 is in the form of an arm extended from the line space driving shaft 14 having front and rear bearings 15 and 16, the bearing 16 being in the form of an extension of what may be termed a rear line space bracket 17 screwed or otherwise secured to the combination bracket 8. 5

10 Adjacent to its rear end the shaft 14 is provided with an arm 18 upon which is imposed a plunger 19 mounted to reciprocate in a cylindrical plunger chamber 20 formed in the bracket 17 and downward or reciprocal movement of the arm 18 is limited by a stop 16^a projecting from the arm and engaging the bearing 16 and this reciprocal movement is assisted by a retracting spring 16^b interposed between the hub of the arm 18 and 15 the bearing 16. The plunger 19 underlies the rear end of a transfer arm 21 constantly urged downwardly by a spring 22 located within the chamber 20. (See Figs. 3, 4 and 6). The transfer arm 21 is fitted upon one 20 flange 23 of a hub 24 having a second flange 25 upon which is fitted the driving arm 26. The arms 21 and 26 and the hub 24 are designed to move together as a unit and oscillate about the line space shaft 9, being assembled on said shaft immediately adjacent to the right hand face of the combination bracket 8. At the outer end of the driving arm 26 is a laterally disposed pin 27 which 25 engages the bifurcated upper end 28 of the line space pawl 29. The pawl 29 is fulcrumed upon a fulcrum screw 30 extended from a pawl carrier 31 in the form of an arm mounted to swing from the line space shaft 9 and disposed close against the face 30 of the driving arm 26, the pin 27 of which extends past the pawl carrier 31 to engage the notched or bifurcated end of the pawl, as already stated and as clearly shown in Fig. 3. If desired, the fulcrum screw 30 35 may be surrounded by a wear sleeve 32, indicated in Fig. 7. The working face 33 of the line space pawl 29 is knurled to engage the knurled periphery of the line space wheel 34 secured to one flange 35 of a hub 36 keyed 40 to the line space shaft 9 as by a pin 37 which passes through the opposite flange 38 on which is secured a collar 39. It will now be seen that the arm 21, hub 24 and arm 26 are rigidly connected to form a line space driver 45 which rocks about the line space shaft 9 as an axis and that the wheel 34, hub 36 and collar 39 are likewise fixedly connected, not only to each other but to the shaft 9 which is the primary driven element of the line spacing mechanism. It will also be seen that the pawl carrier 31 and the pawl 29 swing together from the shaft 9 and serve as an intermittently operative connection between the driving and driven structures. In the 50 normal position of the line spacing pawl, the line spacing wheel 34 is engaged. On the contrary, the pawl is swung to its disengaged position where it is arrested by a stop pin 40 extended from the pawl carrier 31 and engaging a coacting stop 41 on the pawl. 70 The engagement of the line space wheel by the pawl is effected, however, by the initial movement of the driving arm 26, continued movement of which effects the line spacing movement of the wheel 34, shaft 9 and pinions 11 to advance the line space frame 1 75 and the distance between two lines of writing. 80 To insure the return of the pawl carrier 31 to normal position after each actuation thereof, it is provided with a retracting spring 42 having one end secured to the hub of the carrier 31 and its opposite end to a relatively fixed part, as shown in Figs. 2 and 4. 85 It is next in order to describe the means whereby the throw of the line space mechanism may be varied and the distance between the lines of writing thus regulated. This result is obtained by providing front and rear line space stops 43 and 44 between 90 which the line space pawl operates and the distance between which may be varied to determine the extent of the line space movement. The front stop 43 is in the form of a pin projecting from the bracket 8 to engage 95 either the pawl 29, the pawl carrier 31 or both and the variation or adjustment of the line space mechanism is effected by the adjustment of the rear stop 44. This stop is in the form of an arm adjustably mounted on a 100 stop carrier 45 which also is in the form of an arm having a hub 46 which encircles the hub 36 but is movable thereon to allow the stop carrier to swing independently of the hub 36 and the shaft 9. The pivotal mounting of the stop 44 on the carrier 45 includes a headed plunger barrel 47 within which reciprocates a detent plunger 48 having an enlargement 49 backed by a spiral spring 50 surrounding the plunger and incased within 105 the barrel 47. The plunger 48 is normally urged by the spring 50 into engagement with one of a series of recesses or openings 51 in the line space bracket 17, these recesses being disposed in an arcuate series, as shown 110 in Fig. 2, to be engaged by the plunger 48 as the stop carrier 45 is swung to different positions and are spaced apart a sufficient distance to provide fixed or standard line spaces or intervals. The detent plunger 48 is extended beyond the barrel 47 and is threaded for the attachment of a knurled head 52 fitting over the end of the barrel and opposed to the outer face of the stop carrier. 115 The spring 50 exerts a constant tension tending to draw the heads of the plunger barrel and plunger respectively against the outer faces of the stop carrier and stop. This grouping of the parts vastly simplifies this 120 portion of the mechanism since the spring 125 130

itself serves the purpose of both urging the plunger to its engaging position and retaining the elements of this particular group in their assembled relation. In addition to the 5 fixed or standard spacings, it is desirable to provide for intermediate or what is known as universal line spacing. To accomplish this result the stop 44 is mounted for universal adjustment upon, as well as for standard 10 or fixed adjustment with the stop carrier 45. It is for this reason that the stop 44 is made in the form of an arm and swings upon the plunger barrel 47 as an axis, the extreme 15 end of the arm 44 constituting the stop proper disposed to be engaged by the pawl 29 upon the retraction of the latter. By swinging the stop arm 44, the effective portion thereof is urged toward or from the pawl and may be secured at any point between the limits of 20 its swinging movement by a locking screw 53 passed through an arcuate slot 54 in the stop carrier 45 and into a threaded opening 55 in the stop 44. The screw 53 has a knurled head as shown, which bears against the side 25 of the stop carrier as the stop is securely drawn against the carrier and securely locked in its position of intermediate adjustment.

Preparatory to beginning the work, the 30 operator predetermines the width of the line spacing which, if standard, wide, narrow or medium, can be secured by swinging the stop carrier to one of the three standard positions of adjustment. This is done by drawing back the plunger 48 from one of the 35 openings 51 allowing the plunger to snap back into another opening after the stop carrier has been swung the desired distance. If the line spacing desired is not of standard type, any variation can be accommodated by 40 the individual adjustment of the stop 44 to effect which the screw 53 is loosened, the stop swung on its carrier and the screw tightened again. The range of adjustment of the stop 44 is practically equal to the distance 45 between standard spacing so that a truly universal line space adjustment can be secured by the adjustment of the stop carrier or the stop or both. Having predeter- 50 mined the desired line space movement of the machine, the operator, after writing a line, simply depresses the handle 13 which rocks the shaft 14, swings the arms 18 and 21 upward against the resistance of the spring 22 and thereby rocks the hub 24 and the 55 driving arm 26 on the shaft 9. The first part of this movement of the driving arm 26 rocks the pawl 29 into engagement with the periphery of the line space wheel 34 and continued movement of the arm rotates the 60 wheel and with it the shaft 9. Since the rear supporting rollers 10 of the line space frame and the line space pinions 11 are fixed to the shaft 9, rotation of the latter will advance the line space frame, the weight of the 65 frame being supported by the rollers 10 and

the necessary traction secured by the engagement of the pinions 11 with the racks 12 of the track frame. Upon the release of the line space handle or key 13, all of the driving elements of the line spacing mechanism from 70 said handle to the pawl 29 will be retracted by the springs 22 and 42 until the line space pawl comes into contact with and is arrested by the stop 44. The elements of the line space mechanism will then be in condition 75 for a repetition of the described operation.

It is thought that from the foregoing the construction and operation of my line spacing mechanism will be clearly comprehended but I reserve the right to effect such variations of the illustrated structure as may come fairly within the scope of the appended claims.

What I claim is:—

1. In a machine of the class described, the 85 combination with a support and a line space frame movable thereon, of a line space shaft extended across the rear of the frame, a line space driving shaft extending along one side of the frame, line spacing mechanism as- 90 assembled on the line space shaft, a connection between said line spacing mechanism and the rear end of the line space driving shaft, and an operating device carried by the line space driving shaft and located at the front 95 of the line space frame.

2. The combination with a line space frame, of a line space shaft, line space pinions carried by the shaft and line spacing mechanism including driving and driven 100 elements both assembled on the shaft and coacting to rotate the shaft to effect a line spacing movement of the frame, a movable stop carrier supported from the shaft, and a stop mounted on the carrier and limiting the 105 movement of the driving elements.

3. The combination with a line space frame, of a line space shaft, means whereby the rotation of the line space shaft will advance the line space frame, a knurled line 110 space wheel fixed to the shaft, a pawl disposed to engage the line space wheel, a pawl carrier mounted to swing from said shaft, a driving arm also mounted to swing from said shaft and engaging the pawl, a stop carrier mounted to swing about the shaft as an axis, means for retaining the stop carrier in different positions, and a stop mounted on the carrier and coacting with the pawl.

4. A line spacing mechanism including 120 driving and driven elements, of means for limiting the movement of the driving element, said means including a stop carrier adjustable to different positions and a stop mounted on and movable with the carrier 125 and also adjustable to different positions on said carrier.

5. In a line spacing mechanism, the combination with a line spacing wheel, a pawl carrier and a stop carrier both mounted to 130

swing from the axis of the wheel, a pawl pivoted on the pawl carrier and disposed to engage the periphery of the wheel, means for retaining the stop carrier in different positions, a stop in the form of a swinging arm mounted on the stop carrier and coacting with the pawl to determine the extent of movement thereof, and means for retaining the stop in its adjusted positions on the stop carrier.

6. The combination with a line space shaft and a line space driving shaft disposed substantially at right angles to each other, of an arm extended from the driving shaft, a transfer arm mounted to swing about the line space shaft, said arms being co-operatively related, the driving arm movable about the line space shaft with the transfer arm, a pawl carrier mounted to swing about the line space shaft, a pawl mounted on said carrier and engaged by the driving arm, a line space wheel fixed to the line space shaft and engaged by the pawl and relatively adjustable stops for limiting the throw of the pawl.

7. In a line spacing mechanism including driving and driven members, a stop for determining the throw of the driving member, a stop carrier, a detent plunger for retaining the stop carrier in different positions, and means for retaining the stop in different positions of adjustment on the stop carrier.

8. In a line space mechanism, the combination with driving and driven elements, of a stop carrier mounted to swing, a stop mounted to swing on the stop carrier, a detent plunger for retaining the stop carrier in different positions, a barrel for said plunger, said barrel serving as a journal for the stop, and means for retaining the stop in different positions on the stop carrier.

9. In a line space mechanism, the combination of driving and driven elements, of a stop mechanism for determining the throw of the driving elements, said stop mechanism including a stop carrier mounted to swing, a headed plunger barrel passed through the stop carrier, a swinging stop

journaled on the plunger barrel and retained between the head of said barrel and the carrier, a spring urged plunger within the plunger barrel, a head carried by the plunger and opposed to the carrier, means engaging the plunger to retain the carrier in different positions, and means for retaining the stop in different positions on the stop carrier.

10. A line spacing mechanism including a line space shaft, a hub mounted to rotate on said shaft, a transfer arm and a driving arm both fixed to the hub to rotate therewith, a bracket affording a bearing for the shaft and opposed to one end of the hub, a pawl carrier loosely mounted on the shaft and opposed to the other end of the hub, a second hub fixed to the shaft and opposed to the pawl carrier, a line space wheel fixed to the second hub, a pawl carried by the pawl carrier and operated by the driving arm to engage the line space wheel, a stop carrier mounted to swing on the second hub, means for adjustably securing the stop carrier to the bracket, a stop mounted on the stop carrier to engage the pawl, and a collar carried by the second hub and confining the stop carrier thereon.

11. The combination with a line space frame, a pair of brackets at the rear side thereof, a line space shaft journaled in the brackets, rollers and line space pinions carried by the shaft, driving and driven elements both assembled on the shaft, a rear line space bracket detachably secured to one of the brackets first named, a line space driving shaft journaled in said bracket, an operative connection between said line space bracket and the driving shaft and the driving elements mounted on the driving shaft, a stop device, and means for adjustably securing the stop device to the line space bracket.

In testimony whereof I affix my signature in presence of two witnesses.

HARRY ARTHUR FOOTHORAP.
